UNITED STATES PATENT OFFICE.

OSIAS O. KRUH, OF SCHENECTADY, NEW YORK, ASSIGNOR TO GENERAL ELECTRIC COMPANY, A CORPORATION OF NEW YORK.

VAPOR ELECTRIC APPARATUS.

1,104,198.

Specification of Letters Patent.

Patented July 21, 1914.

Application filed December 12, 1903. Serial No. 184,878.

To all whom it may concern:

Be it known that I, OSIAS OTTO KRUH, a subject of the Emperor of Austria-Hungary, residing at Schenectady, county of Schenectady, State of New York, have invented certain new and useful Improvements in Vapor Electric Apparatus, of which the following is a specification.

In vapor electric conductors supplied with current from an alternating current source, and particularly in those provided with a plurality of anodes, difficulty arises under some circumstances due to arcing between the anodes. In apparatus of the character mentioned current flows normally only between each anode and the cathode. Under certain circumstances, as for example if relatively high voltages be employed or if the apparatus be run at an abnormally high temperature, there is apt to be from time to time a more or less severe arcing discharge between the anodes. Such a discharge, even though scarcely more than instantaneous, forms an objectionable short circuit upon the system, and if the current is large enough, might actually injure the apparatus. My invention provides means for overcoming this objection, and thereby permits the apparatus to be worked at far higher voltages than usually employed and without danger due to arcing of the character mentioned. I secure the result mentioned by so arranging the vapor electric device that current cannot pass freely between electrodes performing the same function, but can pass freely between electrodes of different functions. Thus with a plurality of anodes only one of the anodes is capable of allowing current to pass freely. The flow of current through the other anode or anodes is limited by current-reducing means so that only a relatively small current can flow. The main anode therefore carries most of the current to the apparatus while the additional anode or anodes, by furnishing current bridging over the period when the current of the main anode is low or negligible, keeps up the vapor-emitting action of the cathode and so serves to maintain the apparatus in operation. The apparatus as thus arranged is evidently unsymmetrical, by which I mean that it utilizes alternating current pulsations of a single polarity nearly to the exclusion of waves of the opposite polarity. I therefore provide two or more vapor electric de-

vices and arrange them so as to run in multiple with each other and so that one utilizes waves of one polarity mainly and the other waves of the opposite polarity. The apparatus as a whole thus becomes symmetrical in its functions and possesses the valuable advantage of freedom from arcing between the anodes. 60

My invention is capable of application in a wide number of different ways both to circuits involving the use of single phase currents as well as to circuits utilizing multi-phase currents. 65

My invention presents various features of novelty and these features I have endeavored to point out with particularity in the appended claims. 70

The invention itself, however, both as to its practical organization and mode of operation will be better understood by reference to the following description taken in connection with the accompanying drawings in which— 75

Figures 1 to 7, inclusive, illustrate some of the various ways in which my invention may be embodied in practice. 80

In Fig. 1 single-phase alternating current supply mains are indicated at 1 and 2. These mains are employed to supply current to vapor electric devices which, in this case, are employed to rectify the alternating current and supply the same to a consumption circuit consisting of mains 3 and 4 between which translating devices of any desired character are connected. The rectifying apparatus includes two highly exhausted envelopes or receptacles 5 and 6 which may be of glass or other suitable material. Each receptacle is provided with a vaporizable electrode constituting a cathode and with a plurality of co-operating electrodes acting as anodes. In the receptacle 5 the cathode, in this case of mercury, is indicated at 7 while the co-operating anodes are shown at 8, 9 and 10. Of these the anodes 8 and 9 are the main anodes, while the anode 10, in this instance of mercury, is used only in starting the apparatus into operation. The anodes 8 and 9 are supported by glass-enclosed wires or rods 11 and 12 connected with suitable leading-in conductors. The other electrodes 7 and 10 are also provided with leading-in conductors in the usual manner for conveying current thereto through the walls of the envelop. The other envelop 6 is similarly 110

provided with electrodes as indicated at 13, 14, 15 and 16.

One of the main anodes of each envelop is connected directly to one of the alternating current supply mains and the other to the other main. Thus the anode 8 is connected directly to the main 1 and the anode 13 to the main 2. Of the remaining anodes 9 and 14, the anode 9 of the envelop or receptacle 5 is connected with the cathode 15 of the envelop 6, while in a corresponding manner the anode 14 of the envelop 6 is connected to the cathode 7 of the envelop 5. In series with the circuits leading from the respective anodes 9 and 14 I connect current-limiting devices which may be resistances 17 and 18 either inductive or non-inductive.

The cathodes 7 and 15 are respectively connected to the main 3 of the consumption circuit through inductance coils 19 and 20 which act as steadyng devices for enabling the two rectifiers to operate in multiple. These steadyng devices also serve the purpose of deflecting current from one rectifier and causing it to pass through the auxiliary arc of the other rectifier. The opposite side, or main 4, of the consumption circuit is connected to the junction 21 between two reactance coils 22 and 23 in series, as shown, across the supply mains 1 and 2.

In order to start up the system each of the rectifiers is started, one after the other. For the purpose of starting, the rectifier is tipped or shaken so that the mercury of one or the other of the electrodes, such as 7 and 10 of the receptacle 5, flows over the space between them, thus completing an electric circuit from the cathode 7 through the switch 24, which is supposed to be closed at this time, and through a current-limiting resistance 25 to the main 2. As soon as the mercury flows back over the space between the electrodes the metallic connection is broken and thus draws an arc. If the metallic connection happens to be broken at the instant that current is flowing from electrode 10 to electrode 7, then electrode 7 becomes a cathode and, by giving out ionized vapor which is propagated upward therefrom, causes an arc to start between it and the main anode 8.

The other rectifier is then started in a similar manner by closing the switch 26. When this is accomplished the two switches 24 and 26 may be opened, whereupon the arcs between the starting anodes 10 and 16 and the corresponding cathodes 7 and 15 are transferred to the anodes 9 and 14.

It will be noted that the anodes 9 and 14 receive their current, not by direct connection to the mains 1 and 2 as the case may be, but by indirect connection through the corresponding current-limiting devices 17 and 18 and the arcs in the companion rectifiers. That is to say, current for the anode 14 passes from the main 1 through the recep-

tacle 5 to the cathode 7, and then through the current-limiting device 17 before it reaches the anode 14. In the same way current for the anode 9 is received from the main 2 through the rectifier 6 and then 70 through the current-limiting device 18. The current-limiting means, therefore, interferes with and practically prevents any arcing between the anodes. At the same time the current-limiting means allows sufficient current 75 to pass to the anode with which it is related to enable the latter to perform its principal function of securing continuous operation of the main or working anode.

When the apparatus is in operation the inductance coils 22 and 23 operate in a manner, now well understood, to produce a flow of current in either of the rectifiers such as to prevent an interruption of current flow therein as the waves from the source pass 85 through zero, and at the same time cause the energy of both plurality waves from the alternating current source to be utilized.

Instead of accomplishing the object of my invention by connecting one of the anodes of one rectifier or other vapor device, in series with the arc in a companion rectifier, I may secure approximately the same result in a somewhat simpler manner by connecting the two rectifiers in multiple with each other 95 and including current-limiting devices, one in series with one of the anodes of one of the rectifiers and the other in series with one of the anodes of the other rectifier. If the rectifiers are provided with more than 100 two working anodes, as in the case of a three-phase rectifier, all but one of the working anodes of each rectifier will have current-limiting devices in series respectively therewith.

An arrangement such as mentioned is shown in Fig. 2. In this case the two rectifiers 28 and 29 are of substantially the construction described in connection with Fig. 1 and have their respective working anodes connected 110 in multiple to the supply mains 30 and 31 as indicated. One of the anodes of each rectifier has a resistance, either inductive or non-inductive, connected in series with it. These resistances are indicated at 32 and 33, and each serves to limit the amount of current which can pass between the anodes in the corresponding rectifier. The current which can thus pass between the anodes is too small to allow the formation of any appreciable arc and certainly too small to permit a destructive arc. The other features of Fig. 2 which have not been referred to in detail are the same as corresponding portions of Fig. 1, and therefore require no special description.

Fig. 3 shows my invention as applied to a rectifier the same in principle as those already described, but of somewhat different form. The supply system in this case 130

consists of a transformer the primary of which is indicated at 35 and the secondary winding at 36. Instead of the transformer I may, of course, as will be evident to any-
 5 one skilled in the art, make use of a compensator. The mains 37 and 38 extending from the secondary 36 connect with the rectifiers 39 and 40 in exactly the same manner as the mains 1 and 2 of Fig. 1 connect with
 10 the rectifiers 5 and 6. In fact, the only difference in structure which Fig. 3 presents over Fig. 1 is that the consumption circuit 41 has the return lead 42 therefrom connected to the middle point of the secondary
 15 38 instead of to the junction between two reactance coils as in Fig. 1.

Each of the rectifiers in Fig. 3 owes its ability to operate continuously to the corresponding inductance coils 43 and 44. These
 20 inductance coils, in this case, perform the double function of enabling the rectifiers to operate together in multiple, in which case they operate as steadyng devices, and of preventing dead points. In overcoming
 25 dead points the inductance coil for each rectifier stores energy as a current wave passes from one of the anodes and, by re-
 storing energy, causes current to flow so as to bridge over the interval or instant during
 30 which the current from the said anode tends to pass through its zero value. As current tends to rise from zero through the companion anode there is at this instant current already flowing in the rectifier which thus
 35 provides a conducting path and enables current to flow from this anode. The current-limiting devices 45 and 46 operate, however, to limit the amount of current that can pass between the anodes of either rectifier with-
 40 out interfering with the flow of current be-
 tween the main anodes 47 and 48 and their corresponding cathodes 49 and 50.

The arrangement as shown in Fig. 1 is supposed to be started by means of starting
 45 anodes 51 and 52 and the starting arc thus formed to be transferred to one of the non-
 vaporizable anodes. It may be desired, however, to use electrodes all of which are of mercury or of other fluid material. In
 50 this case, each rectifier, as shown in Fig. 4, is provided with a cathode, as at 53 and 54, and with coöperating mercury anodes as at 55 and 56 in the one rectifier and 57 and 58 in the other rectifier. Except in the respects
 55 mentioned the arrangement shown in Fig.
 4 is practically the same as that shown in Fig. 3 and, therefore, requires no further description of details. The apparatus is started as before by shaking or tipping the
 60 respective rectifiers until the starting is accomplished.

In all of the foregoing arrangements each rectifier is shown as provided with anodes each of which receives current directly from
 65 the source. I have found, however, that one

of the anodes, and that one which carries the small current for the purpose of maintaining the other or main anode in operation, may be supplied with current derived solely by an inductive discharge from the 70 energy-storing device traversed by current passing through the main anode. Such an arrangement I have indicated in Fig. 5. In this case the two rectifiers 59 and 60 are each of the same construction as shown in 75 Figs. 1 to 3 and thus require no special description. They are supplied with current, as in Figs. 3 and 4, from the secondary 61 of a transformer or compensator. The anode 62 of one rectifier is connected to one 80 of the terminals of the transformer 61 and the other anode 63 to the other terminal. The respective cathodes 64 and 65 are connected through inductance coils 66 and 67 to the consumption circuit 68, one of the 85 leads 69 of which is connected to the middle point of the secondary 61. The other anodes 70 and 71 are connected respectively through current-limiting devices 72 and 73 to the corresponding inductance coils 66 and 90 67. These inductance coils are charged by current flowing from the main cathodes 64 and 65 of the rectifiers to which they are related, and have discharge paths through the corresponding anodes 70 and 71. Thus 95 if a positive wave passes from the transformer 61 through the anode 62 to the cathode 64 and through the inductance coil 66 back to the middle of the secondary 61, energy will be stored which, as soon as the 100 wave commences to decrease in value, will reappear in the form of a current discharge or arc between the anode 70 and the cathode 64. This discharge lasts over such an interval as still to be in existence when 105 the time comes for the next wave of the same polarity to flow from the secondary 61 to the anode 62. This next wave, therefore, finds a conducting path prepared for it so that the operation of the rectifier goes on 110 indefinitely.

For the purpose of starting I may use starting anodes 74 and 75 of mercury, connected through starting switches 76 and 77 and resistances 78 and 79 to the proper 115 mains as indicated. The function of these starting anodes and the mode of operating the same have already been described in connection with previous figures and require no further elaboration.

Instead of using separate resistances 72 and 73, Fig. 5, one for each of the anodes 70 and 71, I may combine the resistances as shown in Fig. 6. In this figure, the combined resistance which takes the place of 120 the two resistances 72 and 73, is indicated at 125 80. This resistance has one end connected to each of the anodes 81 and 82 corresponding to the anodes 70 and 71 in Fig. 5, and the other end to the main 83 which joins to- 130

gether the two lower ends of inductance coils 84 and 85. The two rectifiers 86 and 87 are in this instance operatively related to two series-connected inductance coils 88 and 89, 5 as in Figs. 1 and 2. The action of these inductance coils will be readily understood from the description relating to Figs. 1 and 2.

In order to reduce the size or amount of 10 the resistance 80 which it is necessary to use to insure freedom from arcing between anodes of the rectifier, the resistance may be connected to the opposite side of the consumption circuit fed by the rectifier. Thus 15 in Fig. 7 the resistance 90, corresponding to the resistance 80 in Fig. 6, is connected as shown at 91 so that current flowing through it must traverse current-consuming devices between the mains 92 and 93 of the consumption circuit. Inasmuch as the resistance 20 of these translating devices supplements that of the resistance 90 the latter resistance need not be of such magnitude as would be required of resistance 80 in Fig. 6. 25 In the foregoing description I have set forth the application of my invention to single-phase apparatus only. It will be evident, however, that my invention is equally applicable to multiphase apparatus. Since 30 it is clear that the novel features of my invention may be embodied in still other forms than those indicated I do not wish to be limited to the exact details shown and described.

35 What I claim as new, and desire to secure by Letters Patent of the United States, is,—

1. The combination of a source of alternating current, a plurality of evacuated receptacles each provided with a cathode and 40 a plurality of anodes, connections between all of the electrodes and said source, and means in circuit with all but one of the working anodes of each receptacle for limiting the flow of current between anodes there- 45 by preventing arcing between the anodes.

2. The method of operating a vapor electric apparatus having a plurality of anodes and a cathode traversed by current from an alternating current source, which consists in allowing the free passage of current from 50 one of the anodes to the cathode and limiting to a relatively small amount the current passing from the other anode or anodes to the cathode.

3. The combination of a plurality of va- 55 por electric devices each having a cathode and a plurality of anodes, a source of supply, connections joining an anode or anodes of one device to said source, connections joining an anode or anodes of the other device in a similar manner to said source, and means in series with an anode of each device for causing an unsymmetrical flow of current from the anodes of each rectifier to the cathode. 60

4. The combination of an exhausted envelop or receptacle, electrodes therein of opposite polarity, one at least of said electrodes being of vaporizable material, a source of alternating current, and means 70 between said electrodes and said source such as to allow the free passage of current waves of one polarity between electrodes of opposite polarity but such as to oppose the passage of current between electrodes of 75 the same polarity.

5. The combination in a vapor electric device for use with alternating current, said device having a cathode and a plurality of anodes whereby current waves of different 80 polarities are transmitted, of means for opposing the flow of waves of one polarity without opposing waves of different polarity.

In witness whereof I have hereunto set 85 my hand this 10th day of December, 1903.

OSIAS O. KRUH.
